COMBINED FACE SHIELD AND MICROPHONE

Allan J. Weltman, Gates Mills, Ohio, assignor to Audio
Link, Inc., Richmond Heights, Ohio

Filed Feb. 27, 1974, Ser. No. 446,483

Term of patent 14 years

Int. Cl. D2—03

U.S. Cl. D2—233

Fig. 1

Fig. 2

Fig. 3

Fig. 4

FIG. 1 is a side perspective view of a combined face shield and microphone embodying my new design;

FIG. 2 is a front elevational view of a second embodiment thereof, an aerial being part of the helmet design, the design being otherwise as shown for the design of FIG. 1;

FIG. 3 is a bottom plan view of the design of FIG. 1;
FIG. 4 is a rear elevational view of the design of FIG. 1.

I claim:

The ornamental design for a combined face shield and microphone, as shown and described.
